DRIVING MECHANISM FOR CASH
REGISTERS

Romano, Burali, Saint - Nicolas d'Aliermont, France; vested in the Alien Property Custodian

Original application March 16, 1939, Serial No. 262,270. Divided and this application June 3, 1941, Serial No. 396,473. In Luxemburg March 18, 1938

3 Claims. (Cl. 192—02)

This invention refers to accounting machines and more particularly to the class thereof known as cash registers, which are provided with indicating mechanism for indicating, for the benefit of both the seller and the customer, items purchased by the customer and entered in the accounting mechanism of the machine operated by the seller, and adding mechanism for accumulating the totals of said items and also controlling various cash transactions effected through the machine by the selling establishment during any desired period, for instance, at the end of the business day.

One object of this invention is to provide two kinds of driving means for the mechanism which adds the item transactions entered in the machine through the keyboard, and for the totalizing mechanism, respectively.

In order that the invention may be more easily understood and readily carried into effect, the same will be described with reference to the accompanying drawings which illustrate an embodiment thereof and are not to be construed in a limiting sense, and in which:

Fig. 1 is a perspective view of a cash register embodying the invention.

Fig. 2 is a diagrammatic perspective showing of different locking means operative either upon depression of one of the amount keys or upon depression of a total key.

Fig. 3 is a diagrammatic perspective view of the mechanism for driving the machine by either a crank handle or an electric motor.

Figs. 4 and 5 are detail views of parts of the driving mechanism, Fig. 4 being a rear view of Fig. 5.

Fig. 6 is a partial transverse vertical section through the machine substantially taken on the line VI—VI of Fig. 1, showing a mechanism which will permit the termination of an electrically started operation in the event of accidental failure of the machine driving motor.

Keyboard mechanism

Referring to Fig. 2, each bank of amount keys numbering from "one" to "nine" inclusive is mounted in an arcuate frame 14—14a concentric with the axis of a shaft 91 and which is screwed or otherwise secured at its lower and upper ends to stationary bars *a* and *b* extending transversely across the machine and rigid with the side walls thereof. The key 17 corresponding to the number "one" is at the bottom of the bank frame and the other bank keys 17a, 17b, 17c, 17d, 17e, 17f, 17g, 17h correspond to the digits from "two" to "nine".

inclusive, respectively. The keys are adapted to slide in ways cut in the outer and inner arcuate flanges 14 and 14a of the frame and when in undepressed position, project from the frame on its outer periphery only, except the key 17h, which, even in its undepressed position, projects from the frame at its inner and outer peripheries for the purpose which will be explained below. Each key is restored to its normal elevation by a spring 18a coiled about its shank 18 between the inner frame flange 14 and a pin 19 extending laterally from the shank 18 to travel a radially elongated slot *c* (Fig. 2) in the left-hand wall of the bank frame. The pin 19 of each key is normally in position to engage an inclined edge *d* of an elongated notch *e* in an arcuate key locking detent plate 22 adjacent the left-hand wall of the bank frame 14—14a and slidable thereon by means of upper and lower slot and stud connections *f*—*g*. In addition to the aforesaid nine keys a zero stop or key shank 29 is provided in the key bank frame 14—14a below the key 17 numbered "1". This zero stop 29 is normally held in depressed position, to project inwardly from the key bank frame 14—14a, by a spring 29c coiled about its shank between the outer frame flange 14a and its pin 19 which traverses an inclined elongated slot *h* formed in the detent plate 22 substantially at a right angle to the notches *e*. At its lower end the detent plate 22 is provided with a lateral projection 28 having a triangular notch 27 and an inclined edge *i* engageable by a latch 26 loosely mounted on a shaft 36.

Upon depression of an amount key, for example the key 17c, its pin 19, by engaging the inclined edge *d* of the detent plate 22, shifts the latter counter-clockwise to cause its upper edges *k* between each pair of notches *e* to block the pins 19 of all undepressed amount keys of the bank and elevate the zero stop 29 against the action of its spring 29c by camming the zero stop pin 19 which is thus forced to move outwards by its engagement with the slot *h* of the shifting detent plate 22; furthermore, this shifting of the detent plate 22, withdraws the inclined edge, *i*, of the lateral projection 28, on which the free end of the latch 26 normally rests, to position the triangular notch 27 opposite the free end of the latch 26, into which the latch drops, thereby locking the detent plate 22 in its elevated position and the remaining keys in that bank in their undepressed positions with respect to the depressed key 17c. When, during the ensuing machine cycle, the latch 26 is thrown out of engagement with the triangular notch 27, the detent plate 22 descends

to its normal position under the action of the spring 29c of the zero stop 29 forcing its pin 19 against the lower edge of the slot *h* in the detent plate 22, thereby releasing all the blocked pins 19 of all amount keys in that bank and restoring the depressed key to its initial undepressed position, the said zero stop 29 returning to its normal depressed position projecting inwardly from the key bank frame 14—14a, so that a new operation of the machine may be effected.

The machine is operated either by means of a crank handle or by means of an electric motor, adapted to rotate a main drive shaft 63 which carries cams and gears for operating all of the mechanisms that are not driven directly by operation of the keys. Rigidly mounted on this shaft are, for example, a gear 46 meshing with a sleeved gear 47 loose on a total and clearing shaft 40.

Each bank of amount keys, of which there are five shown in the machine, is provided with the above described key mechanism driven directly by operation of the keys, and various other mechanisms operated from the main drive shaft 63 such as the driving, differential, adding, totalizing, indicating, (printing) and turn to zero mechanisms, together with various other complementary control mechanisms, interconnected with the said key mechanism for cooperation therewith so as to form a commercially practicable machine (object of the invention).

Close to each latch 26 loose on the shaft 36 and fast on this shaft is a forked arm 35, the prongs 34a and 34b of which are adapted to embrace a pin 33 projecting laterally from a downward extension of the latch 26. Also fast upon the shaft 36 is a bell crank lever or rocker 37 acted upon by a spring 43. A rearward arm of this rocker 37 carries an antifriction roller 41 held in riding engagement with an open cam 42, while the end 37a of the forward arm of this rocker is laterally offset so as to engage an open cam 39 located beside the cam 42. The cams 39 and 42 are fast upon one end of a sleeve 39a loose on the shaft 40, the other end of this sleeve carrying rigid therewith a gear 47 meshing with a gear 46 fast on the drive shaft 63 so that both these gears may rotate with the same angular velocity (Fig. 2). It is evident that under the action of the spring 43 the rocker 37, through the shaft 36, prong 34b of forked arm 35 and pin 33, will press the latch 26 either into the triangular notch 27 or against the inclined edge *i* of the lateral projection 28 on the lower end of the detent plate 22, depending upon whether the latter is in its raised position resulting from full depression of an amount key or in its normal lowered position.

If an amount key is not fully depressed, the detent plate 22 will be insufficiently raised, so that the latch 26, instead of engaging the triangular notch 27, will be slightly moved to the right by the inclined edge *i* (Fig. 4) and its pin 33, by striking the prong 34b, will accordingly move the shaft 36 and with it the rocker 37, the lowermost end 37a of which will then engage the corresponding abrupt shoulder of the cam 39, thereby locking the gears 46 and 47 (Fig. 2) from rotation in the direction of the arrow F₁ and preventing the machine from being operated until the amount key shall have been fully depressed. When this key is properly or fully depressed, the said members will slightly move in the reverse direction aided by the spring 43 acting upon the rocker 37; the upper end of the latch 26 will fall

into the said triangular notch 27 and the lower rocker arm 37a will disengage the cam 39 to enable it to rotate together with the cam 42 and gear 47 under the influence of the gear 46 actuated by the drive shaft 63. Before the cam 42 has made one complete revolution, its dwell portion raises the roller 41 of the rocker 37 rocking the shaft 36 and the forked arm 35, so that the prong 34a thereof, by striking the pin 33 of the latch 26, rocks the latter out of engagement with the triangular notch 27, thereby enabling the key bank mechanism to restore to its normal position. It is to be noted that by a clearance provided between the prongs 34a and 34b, with the pin 33 therebetween, the disengagement of the latch from its detent is effected with a desired delay and at the instant that the cam 42 has made nearly one complete revolution, so that improper depression of an amount key can not adversely affect the operation of the machine. Owing to said clearance, also, operation of one key bank does not affect the keys of any other bank of the machine.

Driving mechanism

As already mentioned, the machine may be operated either by means of a crank handle or by means of an electric motor, either of which will rotate the main drive shaft 63. This involves employment of a special driving mechanism which is located at the right of the machine, at B (Fig. 1) and which will now be described.

Referring to Fig. 3, the crank handle 51 is adapted to be connected at 54 to the outer end of a stud portion provided at its inner end with a disk 56 rigid therewith, carrying coupling pawl 57 on a pin projecting laterally from this disk, the coupling pawl 57 normally resting against the rear edge of a peripheral projection 59 on a disk 60 fast on a stub shaft 60a to which is also fast a pinion 61 in constant mesh with a larger gear 62 fast on the drive shaft 63.

Normally the free end of a detent arm 80 fast on a rotatable supporting rod 79, lies against the opposite or front edge of the projection 59 on the disk 60 to retain the machine locked.

The detent arm 80 may be urged to this position by a suitably pivoted, spring-pressed latch 82 in contact with a lateral extension 85 of the detent arm. A torsion spring 81 encircles the supporting rod 79, one end of which spring is anchored to the tail of the detent 80.

The opposite end of the torsion spring 81 engages a combined locking and releasing arm 78 journaled on the supporting rod 79, to maintain the free end of such locking and releasing arm entered in a notch 76 formed in the periphery of the disk 56 and thus lock the disk and handle against clockwise rotation.

The notch 76 has an abrupt wall, and an inclined wall 76a, as indicated in Fig. 6 when it is desired to operate the crank handle 51 normally in a clockwise direction, the handle must first be started in the opposite direction (arrow F²). Under the camming action of the inclined walls 76a of the disk 56, the locking and releasing arm 78 is dislodged from the notch 76, tensioning the torsion spring 81 to simultaneously displace the detent arm 80 against the tension exerted on the lateral extension 85 by the lower end 84 of the latch 82. The rotatable supporting rod 79 also carries a crank arm 562 and a dog 524 in spaced apart relation which crank and dog are rocked simultaneously with the detent arm 80,

whilst the locking and releasing arm 78 loose on the same shaft is held in its elevated position by a pin 87 projecting laterally from the tail of the detent 80 and the latch 82, in turn, releasably retains the detent in its dislodged position. The hooked end of a spring pressed arresting dog 71, suitably pivoted on the machine frame, lies in position to engage a peripheral shoulder 69 formed on the crank handle disk 51 to limit the initial reverse rotation imparted to the disk 51 by the crank 51 when starting a manually operated machine cycle. From the instant that the arm 71 abuts the shoulder 69 and the direction of rotation of the crank 51 is reversed, the crank handle may be normally operated in a clockwise direction, and the coupling pawl 57 causes the disk 60 and pinion 61 to rotate accordingly, whereby is also rotated, but in the reverse direction indicated by the arrow F³, the main drive shaft 63 through the gear 62 secured thereon and meshing with the pinion 61. In order to reduce the force necessary for driving the machine, the pinion 61 is one-half the diameter of the gear 62, so that two complete revolutions of the crank handle 51 are necessary to accomplish one complete rotation of the drive shaft 63 as required at each operation of the machine.

When the disk 60 has made nearly two revolutions, a projection 67 on a cam disk 68 fast upon the drive shaft 63 wipes past a nose 89 of the rearwardly extending tail of the detent 80, which nose was rocked to the dotted line position shown in Fig. 3 when the detent was disengaged from its disk 58, whereby the lateral extension 85 of this detent 80 is disengaged from the latch 82 and the detent 80 is spring returned to enter its free end in the notch 59b on the disk 60 to stop the rotation of the latter at the end of rotation of the crank, the spring 81, in rocking the detent 80 also operating to rock the locking and releasing arm 78 into the notch 76 on the disk. In this way, the drive shaft 63 and all of the mechanism associated therewith always starts from a well determined initial position and returns exactly thereto at the end of each operation.

When the machine is operated by an electric motor 501, rotation of its armature shaft, through the medium of a series of suitable reducing gears 508, 509, 510, 512, 513, is finally transmitted to an annular clutch gear 515 coaxial with the drive shaft 63 (Figs. 3 and 5). Located within this annular clutch gear 515 and coaxially secured on the drive shaft 63 is a notched clutch disk 516 rotatable by this annular gear 515 only in the direction of the arrow F³ through wedging contact of rollers 517 in notches 518 with the inner periphery of the annular clutch gear 515. Under these conditions, rotation of the drive shaft 63 in the direction of the arrow F³ by the crank handle 51 does not affect the clutch gear 515 and involves only the clutch disk 516 located therein. On the other hand, rotation of the drive shaft 63 in the direction of the arrow F³ by the motor 501 cannot affect the crank handle 51 since the disk 60 in train with the drive shaft 63, rotates idly relatively to the coupling pawl 57, but means must be provided for sharply stopping the drive shaft 63 in precise initial position as heretofore determined by the arresting action of the locking and releasing arm 78 and the detent 80 while the motor continues to exhaust its inertia movement in a few revolutions. To this end, a clutch control disk 522 is loosely mounted on

the drive shaft 63 adjacent the gear 515, supporting laterally projecting pins 521 carrying the clutch rollers 517 in the notches 518 of the disk 516. On the right hand face of this disk 522 is mounted a small lever 593 pivoted on a pin 594 (Figs. 3, 4 and 5) one arm of which extends beyond the periphery of this disk 522, the remaining arm carrying at its end a pin 595 projecting through and movable freely in an elongated slot 596 in the disk 522, the inner end of the pin fitting a hole in the notched disk 516. A tension spring 596, connected at one end to a pin 596a projecting from the disk 522 through a suitable hole in the disk 516, and at the other end to a pin 596b on the disk 516, has for its object to produce from the outset wedging contact of the clutch rollers 517 with the inner periphery of the annular clutch gear 515, since the pins 521 carrying these rollers 517 are fastened to the disk 522 (Fig. 8).
 20 Normally the motor driven annular clutch gear or ring 515, and the motor- or crank-operated clutch disc 516 with its connected circular plate 522, are held disengaged by the clutch-control dog 524 fast on the rotatable supporting rod 79, in the following manner.
 Assume the previous operation of the machine to have been effected by motor, during which the annular clutch gear or ring 515, and the clutch disc 516 with its circular plate 522 have 30 made a complete rotation in the direction of the arrow F³, (Fig. 4).
 As the parts are about to complete such rotation, the outer end of the small lever 593 contacts and is arrested by the tooth 563 of the clutch control dog 526. The clutch members 515, 516 as they complete their rotation, cause a relative movement between the small lever 593 and its circular plate 522, the pivot 594 of the small lever traveling with the circular plate and clutch disc 40 while the outer end of the small lever is held by the dog 524 against advancing.
 The consequent rocking motion of the small lever 593 causes the pin 595 on its inner end to travel ahead a distance (for example) twice as 45 far as that travelled by its pivot 594, depending upon the relative lengths of the respective arms of the lever 593 and the length of the arcuate slot 595a in which the pin 595 of the small lever travels.
 50 This movement of the small lever 593 advances the clutch disc 516 with its drive shaft 63 slightly ahead angularly relatively to the circular plate 522 and against the tension of the spring 596 (Fig. 5) to disengage the clutch rollers 517 from the inner periphery of the annular clutch gear 515.
 Obviously, arrest of the small lever 593 by contact of its pin 595 against the end of the slot 595a in which it travels, arrests the circular plate 522, with its pins 521 (Fig. 4) on which the clutch rollers 517 are mounted, so that the rollers are retained in the wider areas of the cam notches in the clutch disc 516 out of clutching position, thus permitting the motor 501 and the motor driven annular clutch gear 515 to rotate idly until their inertia is lost, while the drive shaft 63 and the clutch disc 516 rigid therewith remain stationary in the required position determined by 60 the engagement of the said small lever 593 (Figs. 6, 7, and 8) with the clutch control dog 524 the nose 563 of which is at right angle to its length to facilitate such arrest. In order to insure proper operation of the driving mechanism, the lever 593 and clutch control dog 524 must be dis-

engaged the very instant that the electric circuit feeding the motor 501 is closed, and must be re-engaged the very instant that the circuit is broken, in synchronism with the respective movements of the detent arm 80 with respect to the disk 60, since the rotation of the drive shaft is transmitted up to this disk 60. This is accomplished in the following manner:

A key 532 (Figs. 1 and 3) is provided for starting the motor 501. By depression of this key, a stud 532a projecting laterally from the key 532 wipes against the bent upper arm portion 535 of a rocker 536 fast upon a shaft 74 and cams the rocker clockwise (Fig. 3) against the tension of a spring 542 to cause a lug 543 projecting from the free end of the arm 535 to enter a notch 77 on the periphery of the crank-operated disk 56, thereby locking the crank handle 51. The rocker itself is locked in its rocked position by engagement of a triangular pin 538 projecting laterally from the end of a depending rocker arm 537 with the nose 644 of a locking member 643, the operation of which will be described later on; it will also be seen later on that the rocker 536 remains in this locked position during each motor-driven operation of the machine.

Referring to Fig. 6, connected to the rocker 536 by a pin 545 is a pawl 544 maintained by a spring 547 in engagement with one of a pair of five-toothed ratchets 531 fast on a shaft 528 rotated step by step by the pawl, each step preferably being about one-tenth of a revolution at each advancing movement of the said rocker 536.

The tooth 574 of a catch 570 is held by a spring 571 connected to the tail of the catch, in yielding engagement with the remaining five-toothed ratchet 531, said catch being pivotally connected to one arm of a suitably supported bell crank 566 and normally resting against an unmutilated portion of that five-toothed ratchet with which it is associated. The remaining arm 565 of the bell crank lies in the path of rotation of a stud 564 projecting from the side of the transmission gear 62 fast on the drive shaft 63, and in the normal rest position, the bell crank operating stud 564 lies just in advance of the end of arm 565 of the bell crank to rock the bell crank against the tension of its return spring 567 at the end of each machine cycle.

To hold the ratchet supporting shaft 528 at the particular points in its rotation to which it may be adjusted, and to limit advances of the shaft to one-tenth of a rotation at each machine cycle, there is provided on the shaft a ten-toothed locking wheel 530 engaged by a dog 550, the toothed end of which is pressed against the locking wheel by a spring 551.

The purpose of advancing the ratchet-carrying shaft upon and incident to the depression of the motor key 532 is to complete the motor circuit, the leads of which as shown in Fig. 3, are connected to the normally spaced apart resilient terminal 558, 559. To this end, a five-lobed cam wheel 529 is fast on the intermittently advanced shaft 528 to co-act with a tappet 553 on a circuit-control switch lever 554 pivoted to the machine frame at 555.

Normally, the tappet 553 of the switch lever 556 is seated in the throat between two of the teeth of the five-lobed switch control cam wheel 529 to maintain an electric conductor 556 on the switch lever disengaged from the spring terminals 558, 559.

A link 561 connects the tail of the circuit control lever 554 and the crank 562 fast on the rotat-

able supporting rod 79 heretofore referred to in the description of the crank operation of the machine, the link connection with the tail of the circuit control lever being slotted to enable the crank operation of the machine to be performed without engaging the motor, and yet permit the circuit control lever 554, when rocked by the cam wheel 529, on the step by step advance of the ratchet shaft 528 under the influence of the motor key 532, to draw the link 561 and crank 562 upwardly and positively rock the supporting rod 79 to cause the clutch control detent 524 to release the clutch 515, 516 for operation.

The lobes of the five-lobed cam wheel 529 upon the step by step rotation of the ratchet shaft 528 by depression of the motor key 532, are successively brought to bear on the tappet 553 on the switch control lever 554 to rock said lever forwardly (clockwise in Fig. 2) to enter its contact member 556 between the circuit terminals 558, 559 and complete the electric motor circuit.

It will be understood that the motor key 532, member 536 and pawl 544 impart one-tenth of a complete rotation to the ratchet shaft 528 and circuit control cam wheel 529, at the termination of which step of rotation, the unmutilated periphery of the cam wheel lies in contact with the high point of the tappet 553 to maintain the circuit controlling switch lever 554 with its contact member 556 between the circuit terminals 558, 559.

Clockwise rocking of the circuit-controlling switch lever 554, raises the link 561 to rock the crank arm 562, supporting rod 79, and clutch detent 524, which detent releases the clutch 515, 516 for operation by the motor 501, and the machine performs its cycle of operation.

Rocking of the supporting rod 79 to release the clutch for operation, also releases the locking arm 80 to free the disk 60 in train with the main drive shaft 63, and the locking arm 80, through its pin 87 displaces the dog 78 which normally locks the crank-operated disk 56 against advance rotation, but the crank-operated disk is prevented from rotating by the lug 543 of the rocker 536.

The unmutilated periphery or high point of that lobe of the switch control cam 529 opposing the tappet 553 maintains the switch lever 554 effective, and the clutch detent 524, the locking arm 80 and the dog 78 ineffective during almost an entire cycle of the machine.

The machine is arrested at the end of a single cycle, and the parts returned to their normal positions, as follows:

It will be recalled that the rearwardly extending arm 565 of the switch-disabling bell crank 566, 565 lies in the path of rotation of a stud 564 projecting laterally from the gear 62 fast on the main drive shaft 63.

As the machine and its main drive shaft have nearly completed a cycle, the stud 564 rotating in counter-clockwise direction, Fig. 3, contacts with and rocks clockwise the rearwardly extending arm of the bell crank 565, 566 against the tension of its restoring spring 567, to draw the catch 570 forwardly. The tooth 574 of the catch 570 normally rests on the top of one of the teeth of its associated ratchet 551. On the occasion of imparting a one-tenth rotation to the ratchet shaft 528 when starting the machine, by depression of the motor key 532 and operation of the rocker 536, the ratchet 531 associated with the catch 570 was advanced one step, to locate one of its inter-dental spaces in position to be entered

by the tooth 574 of the catch, under the tension of the spring 571.

As the catch 570 is drawn forwardly near the end of a machine cycle, it effects a one-tenth rotation of the ratchet wheels 531 and their shaft 528 which turns the lobed cam wheel 529 fast thereon a like distance, to present an interlobed space to the tappet 553 on the switch lever 554.

Incidentally at this time the ratchet 531 associated with the driving pawl 544 connected with the rocker 536 is advanced to present an interdental space to the driving end of its pawl preparatory to the initiation of the next motor driven operation of the machine.

Substantially coincident with the presentation of the interlobed space of the cam wheel 529 to the tappet 553 the cam 67 on the periphery of the restoring disc 66 on the main drive shaft 63, wipes over the nose 89 on the rearward extension of the locking arm 80 to restore the locking arm to its effective position and rotate the supporting rod 79, rocking the crank arm 56 fast thereon counter-clockwise (Fig. 3) which draws the link 561 downwardly and disengages the switch lever 554 and its conductor 556 from the motor circuit terminals 558, 559.

Incidentally, the return of the locking arm 80 with its lateral pin 87 to normal position, frees the dog 78 which is returned by spring 81 to locking engagement with the crank-operated disc 56.

The switch lever 554 in its circuit-breaking travel counter-clockwise fits its tappet into the space between the lobes of the cam wheel 529 preparatory to the next motor-driven machine cycle.

Also the supporting rod 79 on its rotation under the influence of the restoring disk 66, rocks the clutch detent 524 to position its tooth 563 in the path of the outer end of the trip lever 593 on the circular clutch plate 522 to disengage the clutch members 515, 516 at the end of a machine cycle, as already explained.

Finally, as the main drive shaft 63 is coming to rest, it rotates its gear 62 a sufficient distance to enable the lateral stud 564 thereon to escape past the free rear end of the rearwardly extending arm 565 of the bell crank lever 565, 566 whereupon spring 567 restores the bell crank to normal position and thrusts the draft catch 570 rearwardly.

The tooth 574 of the draft catch is inclined to ride out of the interdental space in its associated ratchet 531 so that the point of the tooth 574 again lies on top of one of the ratchet teeth.

Obviously, the normal position of the switch disabling bell crank 565, 566 is such that it will be rocked by the stud 564 at each machine cycle, whether crank-operated or motor-driven, and equally obvious, it would be most undesirable to effect a step rotation of the ratchet shaft 528 at each crank-operated cycle.

This disadvantage is avoided by providing a five-toothed ratchet wheel 531 and advancing it but one-tenth of a rotation, as a result of which, the one-tenth throw of the draft catch 570 during crank-operated cyclings merely causes the tooth of the catch to ride idly back and forth upon the top of the particular ratchet tooth on which it may rest at that time and it is not until after the draft ratchet 531 is advanced by depression of the motor key 532, that the draft catch 570, can operatively engage the succeeding interdental space of its ratchet 531.

Lastly, it will be recalled that the motor key 532, upon depression, swings the rocker 536 caus-

ing its lug 543, to lock the crank-operated disc 56 and hence the crank 51 against rotation, and that a spring-pressed latch 643, 644 takes over the pin 538 of the rocker 536 to maintain it in operated position.

It will also be noted that the lug 543 of the rocker is of a width too great to fit in any of the recesses in the periphery of the crank-operated disc other than the particular notch 71 appropriate therefor, and thus prevents depression of the motor key during a crank-operated cycle.

The rocker and its connected parts also serve as an interlock between the motor key and other manually operable elements of the machine to prevent improper operations.

The motor key, upon removal of the operator's finger, is restored immediately to normal position under the tension of its spring, but the rocker 536 remains in latched position.

Means is provided to automatically effect the release of the rocker 536 at the end of a motor driven operation as follows:

It will be recalled that the drive shaft 63 is provided with a gear 46 (Fig. 3) in constant mesh with a second gear 47 fast on one end of a sleeve, journaled on the totaling and clearing shaft 40.

Cams 39 and 42 fast on the opposite end of the sleeve coact respectively with the opposite relatively offset ends of a substantially U-shaped arm 31, 37a, secured at its intermediate portion to the keyboard controlled shaft 36 extending transversely of the machine.

As the machine is completing its cycle, cam 42 rotating at the same speed as the main drive shaft 63, contacts a roll 41 on the rearmost arm 37 of the U-shaped member to rock the keyboard control shaft 36 clockwise (Fig. 3) primarily to effect release of the depressed numeral keys of the machine.

However, the total key locking member 589 is fast on the keyboard control shaft 36 at some distance to the right of the intermeshing gears 46, 47, and carries a laterally extending pin 589c projecting into proximity to an arm 645 of the latch 644 which locks the rocker 536 in operated position, which latch is journaled near the right hand end of the keyboard control shaft 36.

Therefore, when the keyboard control shaft is rocked clockwise by the releasing cam 42, it rocks the total key locking member 589 which, in turn, presses its pin 589c against the arm of the latch 643 to cause it to release the rocker 536, whereupon spring 542 restores the rocker to its normal position, drawing the lug 543 of the rocker out of the notch 71 of the crank locking disc, and retracting the drive pawl 544 relatively to its associated five-toothed ratchet 531 to position the pawl opposite the following tooth of the ratchet preparatory to the next motor driven operation of the machine.

With the mechanisms hereinbefore described it is possible to enter the desired item in the machine by depressing the proper key on the keyboard and giving the drive shaft 63 one complete revolution either by means of the crank handle 51 or by depression of the starting key 532 controlling operation of the motor 501.

The printing mechanism is located in the space c at the left of the keyboard A of the machine (Fig. 1) and operated through the drive shaft 63 extended to the left (Fig. 2) and extensions, also to the left, of a series of nested sleeves surrounding the shaft 158a, each sleeve having at its inner end a pinion 157 driven by the differential mechanism and a pinion 159 at its outer end (159a,

159b and so on up to the full capacity of the machine), said pinions being rigid with their respective sleeves. The pinions 157 and 159 have the same number of teeth, and hence the same angular extent of movement.

Furthermore, the drive shaft 63 transmits its rotation to a mechanism controlled by an arm 355a (Fig. 2) which, when in raised position, controls the mechanism for item transactions, printing the same and totalizing multi-item transactions, and when in depressed position, controls the mechanism for printing totals of multi-item transactions and turning to zero the multi-item totalizer.

The mechanism for entering item transactions, printing the same and totalizing a number of item transactions and on the other hand, the mechanism for printing totals of multi-item transactions and turning to zero the multi-item totalizer form no part of the present invention. The specific arrangement of both mechanisms is fully illustrated and described in the application filed March 16, 1939, Serial No. 262,270 by the applicant, R. Burali, for "Cash registers."

"Total" key mechanism

The arm 355a may be provided with a key top to form what may be termed a "total key" 355 at the left portion of the machine (Fig. 1).

The arm 355a is rigidly mounted on the above mentioned total control shaft 40 (Fig. 2). Fast to this shaft are hubs 358 of two bell crank levers or rockers 356 and 357 rigidly connected at their respective opposite ends by rods 359 and 360. The bell cranks 356, 357 and the connecting rods 359, 360 constitute a rocking frame fast on and rocking with the total control shaft 40. Journaled upon the rod 359 is a sleeve carrying at its ends a pair of pinions 361. Normally, these pinions 361 are adapted to be driven by a gear 363 fast on the drive shaft 63 and they drive, in turn, a gear 364 fast on a shaft 63a in alignment with the drive shaft 63. Journaled upon the rod 360 is a sleeve carrying at its ends a pair of pinions 362 adapted to be driven by the said gear 363 when the rocking frame 356, 357, 359, 360 is rocked clockwise (Fig. 2) by depression of the total key 355, and these pinions 362, in turn, drive a gear 369 rigid with a sleeve 63b journaled on the shaft 63a. The pair of pinions 361 is in mesh with the gears 363 and 364 when the key 355 is in its elevated or normal position, i. e. in the position corresponding to item operations and in this case, the mechanism to control such operations is evidently driven from the shaft 63a, while the pair of pinions 362 will be in mesh with the gears 363 and 369 when the total key 355 is in its depressed position, i. e. in the position corresponding to "total" operations and in this case the mechanism to control such operations will evidently be driven from the sleeve 63b.

It is important that the total key 355 and its control mechanism be locked in either of these positions at the very instant that the drive shaft 63 is started and until the end of its rotation. This is accomplished by means of a cam 459 fast upon the drive shaft 63, a pawl lever 455 pressed by a spring 458 against this cam 459, and arms 462 and 463 fast on a stub shaft 420, the arm 463 being forked to straddle an extension 465 of the rod 360 of the rocking frame.

The normal position of the total key 355 under control of the spring 481 determines the normal position of the rod extension 465 in the fork 464 of the arm 463 to elevate the free end

of the arm 462 to its high position. When the drive shaft 63 starts rotating in the direction of the arrow F³, its eccentric 459 rocks the end 457 of the pawl lever 455 out of the notch 460 to bring the lever nose 461 against the lower face 462a of the arm 462, thereby locking the latter in this position, i. e. in the normal position of the total key 355, until the end of the operation.

- 10 Depression of the total key 355 rotates the shaft 40 which, in its turn, rotates an arm 581 fast thereon at the other end of the machine. A triangular pin 586 projecting laterally from the arm 581 lifts the nose 589d of a lever 589 fast upon the shaft 36 oscillated by the rocker 37, as previously explained, and at the end of this rocking movement the pin 586 is engaged behind this nose 589d, thereby maintaining the total key 355 in its depressed position at the same time, the rod extension 465, by acting upon the fork 464 of arm 463, rocks the free end of the arm 462 to its low position, so that when the drive shaft 63 starts again to rotate in the direction of the arrow F³ the cam 459 again rocks the arm 457 of the pawl lever 455 to bring the end 461 thereof against the upper face 462b of the arm 462, thereby locking the latter in this position, i. e. in the depressed position of the total key 355, until the end 457 of the pawl lever urged by the spring 458 will have dropped into the notch on the cam 459 at the end of the operation. At this very instant the cams 39 and 42 rotated from the drive shaft 63, as hereinbefore described, cause the rocker 37 to rotate the shaft 36 and with it the lever 589 fast thereon in the opposite direction, thereby disengaging the lever 589 from the triangular pin 586 of the arm 581 fast on the shaft 40 to restore, with the aid of the spring 481 acting upon the bell crank lever 357, the total key 355 and the mechanism dependent thereon to its normal position. However, when the total key 355 is in its depressed position and before the drive shaft 63 has commenced to rotate, it is possible to restore the total key 355 to its normal position by depression of an adjustment or release key 44 (Fig. 1), as will be described later on.

According to the invention, no amount key of the machine can be depressed if the "total" key 355 is depressed, and vice-versa. The hubs 358 of the rocking frame being fast on the shaft 40, depression of the total key 355 rotates an arm 367 (Fig. 2) rigid with the shaft 40 and causes the upper nose of this arm 367, by its engagement with the upper edge *j* of the lateral projection 28 on the detent plate 22, to lock the latter in its normal position. Under these conditions, it will be seen that if an amount key has already been depressed, the "total" key 355 cannot be depressed, since the upper nose of arm 367 would then abut the rear edge *l* of the projection 28 and thus prevents rotation of the shaft 40. Conversely, if the total key 355 is depressed, the upper nose of arm 367 overlies the edge *k* of the projection 28, the detent plate 22 cannot be raised and, therefore, no amount key can be depressed.

Adjustment key mechanism

Referring to Figs. 1, 2 and 6, there is illustrated a mechanism to permit adjustment of various parts and the mechanisms hereinbefore described, controlled by the adjustment or release key 44.

The release key 44, extending from the machine (Fig. 1) includes a key top rigid with the

upper arm 44a of a bell crank lever loosely mounted on the shaft 36, the lower arm of which bell crank carries a pin 45 extending in front or adapted to engage the lower arm 37a of the rocker 37 so as to oscillate the shaft 36 about 14 degrees when the release key 44 is depressed. In the vicinity of the afore-mentioned total key locking lever 589 a lever 640—641 is journaled on the shaft 36, one arm 641 of which carries a pin 642 projecting laterally therefrom and having attached to its end one end of a spring 589b, the other end of which is attached to the lower end of the lever 589 whereby the arm 641 is constantly held against a pin 589a projecting laterally from the lower end of the lever 589. Projecting laterally from the release key arm 44a is a pin 44c adapted to rest against the said arm 641 carrying the pin 642. Attached to the end of the pin 44c is one end of a spring 542, the other end of which is attached to the end of an arm fast upon the shaft 74 on which is secured the interlocking rocker 536 (above described with reference to Fig. 3), so as to urge the release key 44 upwards and the rocker 536 to its normal position. Loose upon the shaft 36 is also a forked latch 643 against one prong 644 of which rests a triangular pin 538 laterally projecting from the rocker 536, when the latter is oscillated by depression of the motor key 532 for controlling the motor 501 (Fig. 3). A second prong 645 of the forked latch 643 is adapted to be engaged by a pin 589c projecting laterally from the head of lever 589, while a third prong 645a is adapted to be held in normal position by a fixed frame pin 652 under the action of a spring 647 connecting the latter with a pin 646 projecting laterally from the forked latch 643. In an opening through the right frame of the machine is a rotatable knob 653 kerfed at its outer end, as at 651 and, secured thereto within the machine is an arm 649 having a right angled nose 650 the arm being held in normal position (Fig. 6) by a spring 654 connecting the nose 650 with a fixed frame pin, said arm 649 being operable to the latch through a pin 648 projecting laterally from the forked latch 643.

The operation of this mechanism is as follows: It has previously been explained that the latch 26 normally rests against the upper face *i* of the cam projection 28 on the detent plate 22 and depression of an amount key by operating the detent plate causes the latch 26, prior to its engagement with the notch 27, slightly to rock the shaft 36, (about 5 degrees) clockwise whereby the lever 589 and with it the lever 640—641 are moved accordingly so that the end 649 of the latter, by engagement with a notch 583a at the end of a locking arm fast on the shaft 74 (Fig. 6), locks the rocker 536 from being operated by the motor controlling key 532 until the latch 26 will have definitely been brought either to its normal position or into its engagement with the notch 27; in other words, the motor 501 cannot be started as long as an amount key is incompletely depressed.

As previously stated, depression of the "total" key 355 causes the arm 581 to rotate in a clockwise direction, as viewed in Fig. 2 (or in a counter-clockwise direction as viewed in Fig. 6), whereby the end 584 of this arm is moved in a path beneath the nose 583 of a second locking arm 582 fast on the rocker shaft 74, from its initial position corresponding to the normal or high position of the "total" key 355 to its final position behind the inner edge 583b (Fig. 6) of the nose of said second locking arm corresponding to full

depression of the "total" key 355. It is evident that with the "total" key 355 incompletely depressed the motor controlling key 532 cannot be fully depressed and, therefore, the motor 501 cannot be started, since the nose 583 of said second locking arm will then abut the end 584 of the arm 581, and that with the motor controlling key 532 fully depressed the "total" key 355 will be locked either in its normal or high position, or in its depressed position, since the nose 583 of the said second locking arm 582, by being lowered, will then engage either the left side or the right side of the end 584 of the arm 581. Thus proper operation of both keys will be insured. It is to be noted that while the arm 581 is moved, as just described, its triangular pin 538, by engagement with the nose 589d of the lever 589, will slightly move the lever 589 and with it the shaft 36 so as to bring the arm 37a (Fig. 2) of the rocker 37 in engagement with the cam 39, thereby locking the machine during the passage of the "total" key 355 from one of its extreme positions to the other. However as soon as this key is fully depressed, the action of the spring 43 will rotate the shaft 36 and with it the lever 589 back to normal position, but the triangular pin 538 will remain engaged behind the nose 589d, thereby maintaining the "total" key 355 in its depressed position; at the end of the operation, by joint action of the cams 39, 42 upon the rocker 37 and shaft 36, the triangular pin 538 will be disengaged from the nose 589d, thereby permitting the spring 481 to restore the "total" key 355 to its normal or high position.

If depression of the "total" key 355 is followed by direct depression of the adjustment key 44 before setting in motion the drive shaft 63, the pin 44c, by pressing against the arm 641 carrying the pin 642 on the lever 640—641, causes the latter to press against the pin 589a to rock the lever 589, thereby disengaging the triangular pin 538 from the nose 589d and permitting the depressed "total" key 355 to be restored to its normal or high position by the spring 481. If, on the contrary, an amount key has been depressed instead of the "total" key, the lever 589 will cause the shaft 36 to rotate through an angle sufficient to force, through the medium of the forked arm 35 and elements associated therewith, the latch 26 to move about the shaft 36 to disengage from the detent plate 22, whereupon the detent plate and the depressed amount key are returned to their normal positions, as hereinbefore described.

It is to be noted that the adjustment key 44 must not be depressed when the machine has already started to operate, since the cams 39 and 42 once started then control the oscillation of the rocker 37, shaft 36 and lever 589, but it will be useful to depress this key before starting an operation to adjust various parts of the machine with respect to one another, thereby insuring efficient operation thereof.

It may happen that for any reason, for example, accidental break-down of the motor circuit, the motor suddenly stops at an intermediate point in a motor-driven operation. The rocker 536 being then latched in its depressed position with its lug 543 in locking engagement with the notch 77, it will be impossible to complete the motor-initiated operation by means of the crank handle 51 as long as the rocker 536 is not restored to its normal undepressed position (Figs. 2, 3 and 5). To accomplish such restoration it will be sufficient to disengage the triangular pin 538 rigid with the rocker 536 from the hooked end 644 of the latch

643 to this end, any suitable key or a knife blade may be introduced into the kerf 651 on the above described rotatable knob 653 to rotate the arm 649 rigid therewith so as to engage the pin 648, thereby rocking the latch 643 out of engagement with the triangular pin 538; the arm 649 will be restored to its normal position by the spring 654.

While the form of mechanism herein shown and described is admirably adapted to fulfil the objects primarily stated, it is to be understood that it is not intended to confine the invention to the one form or embodiment herein disclosed, for it is susceptible of embodiment in various forms all coming within the scope of the appended claims.

What is claimed is:

1. In a machine of the character described having a main drive shaft, a motor for rotating said shaft and a switch, operated from a key, to energize the motor, the combination of a crank handle for manually rotating the main drive shaft; unidirectional coupling means operatively interposed between the crank handle and the main drive shaft, for rotating said shaft in one direction, adapted to allow free rotation of the shaft from the motor in the same direction; and means responsive to operative movement of the crank handle interposed between the switch operating key and the crank handle, for locking the latter against manual rotation to drive the shaft when the switch operating key is moved to operative position, and for locking the switch operating key in inoperative position to prevent starting of the motor when the crank handle is rotated to drive the main drive shaft.

2. In a machine of the type described having a main shaft, a motor for rotating said shaft, a switch operating key for controlling the motor and means for manually rotating said shaft, the combination of means between the said key and the manually actuated means for locking the latter means against manual operation when the key is in operative position; and emergency means for rendering the locking means inoperative in case of a failure of power supply to the motor after the latter has been started and before it has completed its function, so that the operation of the machine can be completed manually.

3. In a machine of the type described having a main shaft, a motor for rotating said shaft, a switch for controlling the motor, a manually operable key for actuating the switch, a crank handle for manually rotating said main shaft, and a free wheel coupling means between the motor and the main shaft for driving the latter in one direction; a cam driven through the main shaft to restore the switch operating key into its inoperative position after the motor has rotated the main shaft by a predetermined amount, a second cam on the main drive shaft, intermediate means operatively interposed between said second cam and the motor controlling switch for switching off the motor and, on the other hand, between said second cam and the free wheel coupling means for stopping said main shaft in a predetermined position, while allowing said motor to slow down gradually.

ROMANO BURALI.
